UNITED STATES PATENT OFFICE.

WILLIAM MEREDITH, OF HUNTINGTON BEACH, AND WALTER L. FOSTER, OF WHITTIER, CALIFORNIA.

TUBING CATCHER.

Application filed December 17, 1921. Serial No. 523,197.

To all whom it may concern:

Be it known that we, WILLIAM MEREDITH, residing at Huntington Beach, in the county of Orange, State of California, and WALTER L. FOSTER, residing at Whittier, in the county of Los Angeles and State of California, both citizens of the United States, have invented new and useful Improvements in a Tubing Catcher, of which the following is a specification.

This invention relates to a device adapted to be mounted upon the tubing extending into a well, and is intended to catch and hold the tubing from dropping into the well, due to accidental parting of the same. It is an object of this invention to provide a tubing catcher which may be clamped upon the tubing and in no way forms a part of the passage through the tubing. It is the practice to provide tubing catchers which comprise a body having a bore, this body being connected into the tubing system so as to be between sections. Upon this body are mounted expanding means for gripping the well casing.

Such constructions require threading the catcher into the tubing in the same way that the section of pipe is placed in the tubing. Our invention is intended to obviate these disadvantages by permitting the catcher to be clamped upon a string of tubing without disassembling the string.

We accomplish these objects by means of the embodiment of our invention illustrated in the accompanying drawing, in which:

Fig. 1 is a perspective view of a tubing catcher mounted upon a section of tubing; and Fig. 2 is a plan view showing the catcher in open position ready to be applied in the string of tubing.

Referring more particularly to the drawing, 3 indicates a section of tubing connected to another section 4 by means of a coupling 5, this being the usual formation of a string of tubing as used in oil wells. The mandrel or body of the catcher is split to form halves 6 and 7, which are similar in construction. The halves are pivotally connected to each other at one end by links as indicated by 8 and 9. Intermediate the ends of the body it is tapered to form an inclined seat for slips to ride upon. When the halves of the body are brought together and held in this position, there is a bore formed extending

completely through the body from end to end. This bore is indicated by 10, and adjacent the top is enlarged to receive the coupling 5 as best shown in Fig. 1. The body is locked upon the tubing by means of screws 12 and 13. The collar formed on the lower part of the body is provided with bores in which are slidably mounted stems 15 and 16. Upon the ends of the stems are slips 17 and 18. The slips have inner faces to conform to the shape of the tapered portion of the body and outer faces which form portions of a cylindrical surface. Teeth are formed upon the outer faces of the slip to engage and grip the casing. It will be noted that upon moving the slips upwardly they are expanded. Below the body is a split sleeve indicated by 19. The sleeve is hinged at one side and is provided with a rib 20 having ends which may overlap and be secured together by means of a bolt 21. Ears 22 and 23 serve for securing the stems 15 and 16 to the sleeve. Interposed between the slips and the collar 14 of the mandrel are compression springs 24 and 25 tending to hold the slips in their upper position. However, the weight of the slips, stems, and sleeves 19 are such as to compress the springs and to hold the slips in a lower position.

On inserting the tubing in the well, at the position that it is desired to place the catcher, the latter is attached in the following manner: The body of the catcher is open as indicated in Fig. 2, as is also the sleeve 19. The catcher is then slipped about the tubing so that a coupling is disposed in the recess 11 and the halves are then brought together. Screws 12 and 13 are tightened and nuts 21 placed in position, thereby securely clamping the catcher to the tubing.

The catcher works in a manner well known. With any sudden and violent movement of the tubing, such as would be caused by the tubing breaking and falling, in accordance with the laws of falling bodies, the weight of both slips and the associated parts with respect to the body becomes zero and the tension of springs 24 and 25 causes the slips to be moved upwardly and outwardly on the body. The expansion of the slips continue until they grip the sides of the casing and prevent further dropping of the tubing.

What we claim is:

1. A tubing catcher comprising a split

body arranged to be clamped about the tubing, and slips slidably mounted on said body so as to be expanded.

2. A tubing catcher comprising a split tapered body arranged to be clamped about the tubing, and slips slidably mounted upon said body so as to be expanded in their movement therealong.

3. A tubing catcher comprising a body split in halves and hinged at one side, recesses in said halves to receive tubing, means to lock the free sides of said halves and thereby clamp said body to the tubing, and slips slidably mounted on said body so as to be expanded.

4. A tubing catcher comprising a tapered body split in halves and hinged at one side, recesses in said halves to receive tubing,

means to lock the free sides of said halves so as to clamp said body to the tubing, and slips slidably mounted on said body so as to be expanded in their movement therealong.

5. A tubing catcher comprising a tapered body split in halves and hinged at one side, there being recesses in said halves with an enlargement at one portion so as to receive tubing and a coupling, means to lock the free sides of said halves and slips slidably mounted on said body so as to be expanded in their movement therealong.

In witness that we claim the foregoing we have hereunto subscribed our names.

WILLIAM MEREDITH.
WALTER L. FOSTER.
